ELECTRON DISCHARGE DEVICE

William H. Painter, East Orange, N. J., assignor
to Radio Corporation of America, a corpora-
tion of Delaware

Application March 30, 1935, Serial No. 13,854

5 Claims. (Cl. 250—163)

My present invention relates in general to an improvement in electronic tube structure and more particularly relates to the mounting of electron beam generating, focusing, and accelerating electrodes within an electronic device of the cathode ray type.

It has been customary in the past to provide in an electron tube of the cathode ray type a structure of electrode elements within the tube by mounting certain of the elements comprising the electron gun upon a reentrant stem. To provide electrical contact with these elements lead wires and spuds were provided in the glass press and the elements were individually and separately attached to these lead wires by welding or other suitable means. The resultant structure had the disadvantage that the electrode members were in many instances non-rigidly supported and that relative motion was possible between the various elements. It is well known in the cathode ray art that accuracy of alignment and spacing of the various tube parts is a prerequisite to efficient operation and that such alignment and spacing has been exceedingly difficult to obtain by the conventional means of support.

Therefore, in accordance with my invention, I have provided a cathode ray device having novel structural features which increase the rigidity of the assembly and thereby improve the operating characteristics of the device. Also, in accordance with my invention, it is possible to provide close electrode spacings which heretofore were very difficult to obtain.

Having in mind the defects of prior art tubes, it is an object of my invention to provide improved supporting means for the elements of a cathode ray tube. It is a further object of my invention to provide an electron tube electrode assembly having the component parts concentrically mounted in a predetermined spaced relationship.

My invention possesses numerous other objects and features which will be set forth in the following description of the invention, and, as will become apparent from reading the specification, many modifications and changes in form may be provided so that I do not intend to limit myself to the specific modifications shown, but believe myself to be entitled to adopt variant embodiments of the invention which fall fairly within the spirit and scope of the appended claims.

The novel features that I consider characteristic of my invention together with the invention itself will best be understood from the following description of certain preferred embodiments

thereof when read in connection with the accompanying drawings in which,

Figure 1 is a view of a cathode ray tube in side elevation embodying one modification of my invention;

Figure 2 is an axial sectional view of one modification of my invention; and,

Figure 3 is an axial sectional view of a second modification of my invention.

If reference is now made to the drawings it will be seen that the foregoing and auxiliary objects are attained by providing according to a preferred embodiment of my invention, a concentric electrode assembly unit by the use of suitable insulating spacers so positioned as to hold the electrodes in a single unit assembly. Specifically the cathode, control grid and electron accelerating elements are provided with flanges whereby these elements are rigidly supported by means of insulating compression members. The electrodes are held rigid by the spacers serving as compression members in the assembly and the entire unit is then supported as a whole from the stem press insuring a maximum of rigidity among the component parts.

Referring now more particularly to the accompanying drawings the cathode ray device comprises the usual sealed and evacuated vessel 10 having a substantially cylindrical neck section 12 and a frusto-conical section 14 terminated by a substantially plane surface 16. The reentrant stem press 18 is used to support the electron gun assembly 20. The electron gun assembly, as shown in more detail by Figure 2, comprises the filament or heater 22, a cathode and control grid assembly 24, an accelerating electrode assembly 26 and an anode assembly 28. Suitable support leads 30—32, one of which may be a current carrying lead, support the gun assembly from the reentrant stem press.

The sub-assemblies, enumerated above, may have current carrying leads designated as 34, 36, 38, and 40 respectively. The tube 10, preferably has incorporated therein beam deflecting plates 42 and 44, which by impressing suitable operating potentials thereon may be made to direct the beam over various portions of the luminescent screen 46 deposited on the inner wall of the end section 16. An auxiliary beam focusing electrode surface 48 is provided on a portion of the inner wall of the vessel terminating in a current carrying lead 50.

That embodiment of my invention shown in Figure 2, as already considered, comprises the cathode-control grid assembly 24, accelerating

electrode assembly 26, and anode assembly 28. It will be seen on reference to the drawing that the cathode-control grid assembly comprises the cylindrical sleeve 52 surrounded by the supporting disc 54. The cathode 23 is provided with an indentation 25 which may contain electron emissive material such as barium or strontium compounds.

The insulating disc 60 is provided with holes 62 thru which may be threaded the filament leads 34 and the cathode lead 36. The cathode is rigidly supported between this disc 60 and a recessed insulating disc 64. These two insulating members are held by compression between the flanged member 66 and the apertured flanged control grid disc 68. The cathode is thus held securely by compression within a predetermined axial distance of the control grid disc, such distance depending upon the recess in the insulator 64.

20 The cathode-control grid assembly 24 is rigidly secured to the accelerating grid assembly 26 in much the same manner as the cathode was positioned within the control grid assembly. The annular apertured disc 54 carrying the cathode-control grid assembly is positioned and spaced from the apertured flanged disc 70, which forms the effective accelerating electrode surface, by the insulating members 72 and 74. These insulators are supported in compression between the flanged members 70 and 76; the entire assembly being retained by the cylindrical sleeve 78.

30 In like manner the accelerating grid-control grid assemblies are supported by the insulating members 80 and 82 between the flanged discs 84 and 86 which are supported in turn by the anode assembly 28 comprising the cylindrical sleeve 88 and apertured discs 90, 92, and 94.

40 A further embodiment of the structure shown in Figure 2 is that shown in Figure 3 wherein the various component parts have similar designations. The cathode-control grid assembly 24 is for all practical purposes the same as that shown in Figure 2 comprising the heater 22, cathode 23 supported by the insulating spacers 60, 64 between the apertured discs 66, 68 and cylindrical sleeve 52. In this modification the entire gun assembly 20 is supported from the stem press 18 by the accelerating electrode assembly 26 through the supports 30, 32 rather than through the anode assembly 28.

50 The accelerating electrode assembly thus rigidly fixes the position of the cathode-control grid assembly 24 by insulating members 72, 74 and the anode assembly by the insulating members 80, 82. This rigidity is insured by holding the insulating members 72, 74, 80, 82 by compression between the flanged discs 96, 98, 100, which are fastened to the accelerating electrode cylinder 78 by welding or other suitable means. In this 60 modification (Fig. 3) provision may be made to supply operating potential to the anode 28 through the flexible current carrying lead 104. The entire electron gun assembly 20, as a single unit, may be supported by the stem 18 through 65 the rods 32. The current carrying lead 104 being

flexible will furnish no material support for the anode, that element being supported by the aforementioned insulating spacers.

It will be apparent to those skilled in the art that the electron gun assembly may be supported from the stem in a number of ways, such as by rods extending to the control grid assembly rather than to the anode or accelerating electrode assembly.

What I claim is:

1. A cathode ray discharge device comprising an enclosing envelope having a stem, a plurality of rods extending from said stem, an anode mounted on said rods, said anode partially enclosing a cathode, control electrode and accelerating electrode mounted in concentric relation with said anode and supported thereby independently of said stem. 10

2. A cathode ray discharge device comprising an enclosing envelope having a stem, a plurality of rods 20 extending from said stem, an accelerating electrode mounted on said rods, said accelerating electrode partially enclosing a cathode and a control electrode and an anode mounted in coaxial relation with said accelerating electrode and supported thereby independently of said stem in a 25 position to at least partially house all of said electrodes.

3. A cathode ray device comprising an enclosing envelope having a stem, a plurality of rods 30 extending from said stem, a control electrode mounted on said rods, said control electrode supporting in compression between concentric insulating spacers, and in coaxial relation therewith, a cathode, accelerating electrode and anode, 35 and said anode being positioned at least partially to surround all of said electrodes.

4. A cathode ray device comprising an enclosing envelope having a stem, a plurality of rods 40 extending from said stem, an anode mounted on said rods, said anode supporting in compression between concentric insulating spacers, and in concentric relation therewith, a cathode, control electrode and an accelerating electrode, said electrode control, accelerating electrode and anode each having apertures located in alignment with the cathode, said apertures being of different diameters. 45

5. An electron tube comprising an enclosing envelope having a stem member at one end thereof, a plurality of current carrying support members secured within the stem portion and protruding inwardly of the envelope, a cold electrode member supported rigidly from the inwardly extending support members and a cathode member 50 also positioned within said envelope and at least partially surrounded by the rigidly supported cold electrode, and a plurality of additional cold electrodes rigidly supported from the first named cold electrode independently of the support stem 55 and in concentric relationship with the first named electrode and the cathode, and also at least partially housing said first named electrodes. 60
